ELECTRIC TERMINAL CONNECTER

Original Filed Feb. 27, 1928

INVENTOR
Charles E. Hoover.

BY
Albert D. Utterich
ATTORNEY

UNITED STATES PATENT OFFICE

CHARLES E. HOOVER, OF LANCASTER, PENNSYLVANIA

ELECTRICAL TERMINAL CONNECTOR

Original application filed February 27, 1928, Serial No. 257,354. Divided and this application filed June 28, 1929. Serial No. 374,355.

My invention relates to the art of electrical connectors and it particularly has for its object to provide certain modifications and improvements on the terminal-post connectors that constitute the subject matter of my application for patent filed October 4, 1927, Serial No. 223,917, and the present application is in particular a division of my application filed February 27, 1928, Serial No. 257,354.

10 The present invention has for its object to provide a terminal-post-cable connector of the general type disclosed in my aforesaid applications with improved clamping faces so designated and constructed as to adapt 15 the connector to take terminal posts either of the straight cylindrical type or of the tapered frusto-conical type and to take such posts of various diameters and maintain a surface contact between the terminal post and 20 the clamp of the cable connector.

Other objects will in part be obvious and in part be pointed out hereinafter.

To the attainment of the aforesaid objects and ends, the invention resides in those novel 25 features of construction, combination and arrangement of parts, all of which will be first fully described in the following detailed description, then be particularly pointed out in the appended claims, reference being had 30 to the accompanying drawings, in which:—

Figure 1 is a perspective view of the invention in use.

Figure 2 is a plan view of the invention.

Figure 3 is an inverted plan view of the 35 same.

Figure 4 is a perspective view of the principal element of the connector showing the bendable plate in the "open" position.

Figure 5 is an elevation of the parts shown 40 in Figure 4 with the flat cable in place before bending down the bendable plate.

Figure 6 is a cross section on the line 6—6 of Figure 3.

Figures 7 and 8 are diagrammatic plan 45 views illustrating the clamp head adjusted to fit minus and plus terminals respectively.

In the drawings, in which like numerals indicate like parts in all of the figures, 1 represents the main jaw of the connector which 50 is relatively fixed and is constituted with a

flat face 2 having a male lug 3, the bolt hole 4 passing through the jaw 1, as indicated.

The jaw 1 has its gripping surface serrated as at 5 and in the embodiment of the invention illustrated it is provided with a 55 relatively rigid flat plate or shank 6 which extends in a direction at an obtuse angle to the plane of the jaw's face 2.

The shank or plate 7 is provided at its extreme end with a pair of side lugs 7 and on 60 its inner face it is provided with teeth 8. The teeth 8 are adapted to pass through apertures in the flat battery cable 20 hereinafter again referred to and project into the slots 10 in the flat bendable plate or shank 9.

The plate 9 has its slots 10 preferably chamfered as at 11 so that when the plate 9 is chamfered down onto the cable 20 with the pins 8 projected into the slots 10 the ends 70 of the pins may be flattened or riveted over 70 and thus lock the plate 9 in place as well as securing the cable 20 in a rigid and electrically good way.

The removable jaw 12 is provided with a bolt hole 23 similar to the bolt hole 4 and 75 it is also provided with a serrated gripping face 13 opposing the face 5 of the other jaw.

The jaw 12 has a recess 14 formed between a pair of spacing lugs 14 α to receive loosely the lug 3 when the parts are assembled. 80

The removable jaw 12 has a flat face 15 opposing the face 2 of the jaw 1.

The jaws are held in their gripping position by a bolt 16 whose head 17 lies against the shoulder 19 formed by the shank 6 and the jaw 1 and is thereby prevented from turning, while a nut 18 serves to draw the jaws together, in cooperation with the bolt 17.

A flat cable 20 is adapted to have the connector secured to it, as before intimated, and 85 21 designates the battery having the usual terminal post 22, the thing that is to be gripped by the jaws 5 and 13 constituting my invention.

As will be observed from the drawings, especially Figures 7 and 8, from which the serrations have been omitted for purposes of clear illustration, the gripping faces of the members 1 and 12 are curved on two centers 100 to provide large or plus terminal gripping

surfaces 24, and small or minus terminal gripping surfaces 25 to adapt the single gripping head for efficiently clamping on either terminal.

- 6 It will be observed that by reason of the fact that the lugs 14 α and 3 have a loose engagement with one another and in view of the fact that the bolt 16 passes loosely through the bolt holes 4, the jaw 12 has a 10 limited amount of universal movement, that is to say, it may rock on the lugs 14 α to open and close the jaws, it may rock sidewise to adapt the jaws to straight or tapering posts, and it may swivel on an axis parallel to the 15 bolt 16 to line up the corrugations of the jaws into parallelism, and it may move backwardly and forwardly to shift the centers of curvature of the jaws to accommodate irregular posts or to allow for irregularities in the 20 casting of the jaws. My construction enables the jaws to be die cast and assembled without any machine work being done on the same, thereby cutting down the manufacturing costs considerably.
- 25 While in this application I have shown and described a particular means of connecting the cable device to the cable 20 I make no claim thereto in this application as that constitutes the subject matter of my original 30 application, Serial No. 257,354 aforesaid.

From the foregoing description, taken in connection with the accompanying drawings, it is thought the complete construction, operation and advantages of my invention will 35 be readily understood by those skilled in the art.

What I claim is:

1. A cable-to-post connector comprising a sleeve for attachment to the end of a cable, 40 a clamp jaw fixed thereto, a separable jaw associated with said fixed jaw, said jaws having opposing post-gripping faces curved on a plurality of centers to adapt said faces to terminal posts of different diameters, said 45 jaws having inter-engaging bearing means at the end remote from said gripping faces, and a bolt with nut passing loosely through apertures in said jaws at a place for securing the same together between the ends of 50 said jaws, said inter-engaging bearing means comprising a male and female bearing having a rocking and sliding adjustable movement whereby said separable jaw may slide longitudinally on said fixed jaw, and may rock laterally and longitudinally to accommodate 55 itself to battery posts of varying diameters and shapes, substantially as and for the purposes described.
2. A cable-to-post connector comprising a sleeve for attachment to the end of a cable, 60 a clamp jaw fixed thereto, a separable jaw associated with said fixed jaw, said jaws having opposing post-gripping faces curved on a plurality of centers to adapt said faces to terminal posts of different diameters, said 65

jaws having inter-engaging bearing means at the end remote from said gripping faces, and a bolt with nut passing loosely through apertures in said jaws at a place for securing the same together between the ends of said jaws, 70 said inter-engaging bearing means comprising a male and female bearing having a rocking and sliding adjustable movement whereby said separable jaw may slide longitudinally on said fixed jaw, and may rock laterally and longitudinally to accommodate 75 itself to battery posts of varying diameters and shapes, said gripping faces being corrugated in the direction of the axis of the jaws, substantially as and for the purposes described.

CHARLES E. HOOVER.
